US0D1057943S

(12) **United States Design Patent** (10) **Patent No.:** **US D1,057,943 S**
(45) **Date of Patent:** **** Jan. 14, 2025**

(54) **PACKAGED OSTOMY ACCESSORY**

(71) Applicant: **Coloplast A/S**, Humlebaek (DK)

(72) Inventor: **Niels Pinholt**, Roskilde (DK)

(73) Assignee: **Coloplast A/S**, Humlebaek (DK)

(**) Term: **15 Years**

(21) Appl. No.: **29/832,340**

(22) Filed: **Mar. 28, 2022**

(57) **CLAIM**

The ornamental design for a packaged ostomy accessory, as shown and described.

DESCRIPTION

FIG. 1 is an isometric view of a design for a packaged ostomy accessory.

FIG. 2 is a top view thereof.

FIG. 3 is a bottom view thereof.

FIG. 4 is a front side view thereof.

FIG. 5 is a back side view thereof.

FIG. 6 is a right side view thereof; and,

FIG. 7 is a left side view thereof.

The portions the article shown in broken lines form no part of the claimed design.

1 Claim, 7 Drawing Sheets
